EJECTOR FORK

Filed Nov 12, 1931

UNITED STATES PATENT OFFICE

THOMAS S. HUTCHISON, OF CHICAGO, ILLINOIS

EJECTOR FORK

Application filed November 12, 1931. Serial No. 574,593.

My invention relates to an improved construction of ejector fork for use generally, which is particularly applicable to culinary purposes.

By my invention, I produce an improved construction of fork of the kind referred to, which is free from concealed or enclosed parts of any kind, is practically frictionless in operation, contains no springs of any kind which can get out of order, which is simple in construction and operation and cheap to manufacture and which at the same time is quite effective in use.

The above and other objects of my invention will best appear by reference to the accompanying drawing showing a preferred embodiment of my invention, in which

Fig. 1 illustrates my improved fork in side elevation,

Fig. 2 is a bottom view of the parts shown in Fig. 1,

Fig. 3 shows in a view similar to Fig. 1, one manner of holding the parts of the fork for one purpose,

Fig. 4 shows in a view similar to Fig. 3, another manner of holding the parts of the fork for another purpose,

Fig. 5 is a sectional view of the parts shown in Figs. 1 and 2 taken along the line 5—5,

Fig. 6 is a sectional view of the parts shown in Figs. 1 and 2 taken along the line 6—6, and

Fig. 7 is a top view of a part of the ejecting member.

Similar numerals refer to similar parts throughout the several views.

As shown in Figs. 1 and 2, my improved fork construction consists of a fork member 10 provided with tines 11, and provided also with a handle 12. The fork member is preferably of flat sheet metal of any desired kind, of the shape indicated, the thickness of the metal being sufficient to give the fork member a desirable degree of stiffness. The shank portion 15 of the fork member is provided with substantially parallel edges as indicated at 13, 13 terminating at shoulders 14, 14 so that the shank portion is narrower than the adjacent portion of the fork member, to receive with a free sliding fit a guiding por-

tion 16 of the ejector member. The guiding portion 16 is in a plane substantially perpendicular to the shank portion 15 of the fork member, and as more clearly shown in Fig. 5, is provided with a slot 16a loosely fitting the shank portion 15 of the fork member. The guiding portion 16 of the ejector member is connected by a strip portion 17 extending towards the tines 11, 11, with an ejector plate 18, which, as more clearly shown in Fig. 6, is provided with edge notches 18a, 18a loosely fitting the tines 11, 11, the ejector plate being in a plane substantially perpendicular to the tines 11, 11. As shown in Figs. 1 and 7, the guiding portion 16 is also connected with an operating extension 19 which projects over the handle 12 and is preferably provided with offset portions 19a and 19b. The handle 12 is preferably provided with a lug 12a extending therefrom towards the ejector extension 19, and in line with the offset portion 19a when the ejector member is in its fully retracted position.

As a result of the construction described, the off-set portions 19a and 19b form a convenient means for engagement by the thumb of the operator, when the fork is grasped as indicated in Fig. 1, so that after a desired article has been impaled on the fork, and it is desired to remove the article therefrom, the ejector member may be moved without appreciable friction or resistance of any kind, by engagement of the thumb with one of the off-set portions 19a and 19b, and movement of the thumb towards the tines 11 of the fork. It will be noted that the extension 19, by projecting over the handle 12 of the fork as described, materially decreases the amount that the thumb must be extended from the hand of the operator, in moving the ejector member as far as the shoulders 14, 14 will permit, which amount of movement with tines of considerable length, would otherwise be difficult to accomplish, particularly for an operator with a small hand, since when the guiding portion 16 of the ejector member is in engagement with the shoulders 14, 14, it is necessary for the ejector plate 18 to be practically at the extreme outer ends of the tines 11, 11, to insure the removal of any article

carried by the fork. It will be observed, that with an ejecting member constructed so that the portion engaged by the operator to move it on the fork, is located at the inner end of the handle, or closer to the tines than the inner end of the handle, it is impossible to avoid a very considerable reaching or extension of the thumb of the operator, where the tines of the fork are of considerable length, as is required for many purposes, for example handling vegetables of considerable size in connection with boiling or baking them. This difficulty, is entirely overcome by my improved construction, since with the handle 12 grasped by the operator in a natural manner, all that is required of the operator to effect an ejecting operation, is, instead of having the thumb rest in its natural position to grasp the handle 12 of the fork, to move the thumb slightly away from the tines 11, so that it is within the hand and in engagement with the off-set portion 19a, so that the thumb is in a position to begin the ejecting operation. As the thumb is moved outwardly it naturally rolls on the extension 19, so that when the ejecting operation is partly completed, the thumb moves into engagement with the off-set portion 19b to complete the ejecting operation, and as a result the hand of the operator is not unduly stretched or extended, perfect control of the fork is retained at all times, and the ejecting operation may be controlled perfectly according to the physical nature of the articles being handled, involving the ease with which they may be split or injured by handling them.

Another important advantage resulting from my construction above described, is illustrated in Figs. 3 and 4. As shown in Fig. 3, the thumb of the operator is illustrated as pressing the off-set portion 19a into engagement with the lug 12a carried by the handle 12, which is a condition readily effected by the operator if desired, and readily permitted by the resilient nature of the strip portion 17 of the ejector member. With this condition, movement of the ejector member on the fork portion is prevented, and the fork may be used in the same manner as though the ejector member were not a part of it, which is of advantage in some cases. For example, with some articles, the tines 11, 11 have but a slight hold on the articles, and there is a constant tendency for the articles to slip from the tines. In such cases, the slight impact due to the ejector member dropping against the articles, might be sufficient to dislodge them from the fork, and in such cases, holding the ejector member as described in connection with Fig. 3, prevents such an occurrence. Again, with certain articles handled by the fork, it is desirable that the tines shall not be inserted more than a certain distance into the articles, on account of the dan-

ger of splitting the articles, and in such cases the extension 19 of the ejector member is handled similarly to the manner described in connection with Fig. 3, excepting that the ejector member is moved towards the tines 11, 11 until the off-set portion 19b is in alignment with the lug 12a for which condition the extension 19 is pressed into engagement with the lug 12a as described for the off-set portion 19a in connection with Fig. 3. By this means, I am able to secure all of the advantages of a short tined fork and a long tined fork in the same structure.

The ejector member described is preferably made of sheet metal so that it may be formed in a single piece, and the outer surfaces of the off-set portions 19a and 19b are preferably roughened in any convenient manner, to facilitate positive engagement of the hand of the operator with them. The strip portion 17 of the ejector member is of sufficient width and thickness to positively operate the ejector plate 18, and yet slender and resilient enough to yield readily laterally to permit engagement of the off-set portions 19a and 19b with the lug 12a for a slight pressure exerted on the extension portion 19 of the ejector member. The ejector member is preferably mounted on the fork member 10, before the handle 12 is secured to the shank 15 of the fork member. The handle 12 is preferably of metal, and may either be solid or hollow as desired, and in any event, the handle and shank 15 are preferably secured together by welding or brazing to insure a water tight connection between these two parts. In this manner, since the material of the handle is continuous and without perforations of any kind, and the connection between the handle and shank 15 is tightly sealed, no opportunity is afforded for moisture, grease and organic matter to collect in the joint or in the handle and produce an unhygienic condition. It will also be observed that the fork member and the ejector member are of extreme simplicity, that all parts of them are readily accessible for cleaning purposes, and that the device may be readily manufactured by simple mechanical operations and from inexpensive material.

It will be understood that the fork may be handled in any desired manner and that the ejector member may be operated in any manner desired; also that the fork may be made in any desired size and of any desired material or materials, and used for any purpose for which forks generally are susceptible of use.

While I have shown my invention in the particular embodiment above described, it will be understood that I do not limit myself to this exact construction as I may employ equivalents known to the art at the time of the filing of this application without depart-

ing from the scope of the appended claims.

What I claim is:

1. In an ejector fork, the combination of a fork member having tines and a shank portion, a handle on said shank portion, said handle having a lug extending laterally therefrom, and an ejector member comprising an ejector plate having edge notches in sliding engagement with said tines, a slotted 10 guiding portion freely movable on said shank portion, a strip portion connecting said ejector plate and said guiding portion, and an extension portion projecting from said guiding portion over said lug, said extension portion having spaced off-set portions for engagement selectively with said lug for different positions of said ejector plate on said tines.

2. In an ejector fork, the combination of 20 a fork member having tines and a shank portion, a handle on said shank portion, said handle having a lug extending laterally therefrom, and an ejector member comprising an ejector plate having edge notches in 25 sliding engagement with said tines, a slotted guiding portion freely movable on said shank portion, a strip portion connecting said ejector plate and said guiding portion, and an extension portion projecting from said 30 guiding portion over said lug, said extension portion having spaced off-set portions for engagement selectively with said lug for different positions of said ejector plate on said tines, the parts of said ejector member 35 in their unstressed condition holding said extension portion out of engagement with said lug, and said strip portion being resilient laterally and yielding for engagement between said lug and a desired one of said 40 off-set portions.

3. In an ejector fork, the combination of a fork member having tines and a shank portion, a handle on said shank portion, said handle having a lug extending laterally 45 therefrom, and an ejector member comprising an ejector plate having edge notches in sliding engagement with said tines, a slotted guiding portion freely movable on said shank portion, a strip portion connecting 50 said ejector plate and said guiding portion, and an extension portion projecting from said guiding portion over said lug, said extension portion having spaced off-set portions for engagement selectively with said lug for 55 different positions of said ejector plate on said tines, said off-set portions providing for successive and continuous engagement therewith by the operator's hand holding the fork during an ejecting operation.

40 In witness whereof, I hereby subscribe my name this 9th day of November, A. D. 1931.

THOMAS S. HUTCHISON.
